UNITED STATES PATENT OFFICE.

SAMUEL G. RHODES, OF NEW YORK, N. Y., ASSIGNOR TO THOMAS E. MURRAY, OF NEW YORK, N. Y.

ELECTRIC TIME MECHANISM.

1,120,241.

Specification of Letters Patent. Patented Dec. 8, 1914.

Application filed October 17, 1912. Serial No. 726,286.

To all whom it may concern:

Be it known that I, SAMUEL G. RHODES, a citizen of the United States, residing at New York, in the county of New York and State of New York, have invented a certain new and useful Improvement in Electric Time Mechanism, of which the following is a specification.

The invention relates to an electric time mechanism, and consists in the circuit-controlling device, associated with the pendulum, whereby circuit to the motor-magnet, actuating said pendulum, is alternately broken and closed.

In the accompanying drawings—Figure 1 is a front, and Fig. 2 a side elevation, of my electric time mechanism. Figs. 3 and 4 are detailed views, showing two positions of the pendulum and circuit-controlling device.

Similar numbers of reference indicate like parts.

The motor-electro-magnet 1 is adjustable on the threaded rod 2, projecting from the supporting back-board 3. The curved plate armature 4 of the magnet is disposed below the same, and is carried by a bent arm 5, which is secured to a bar 6, preferably of insulating material, which bar 6 is suspended by leaf springs 7 from a bar 8 protruding from the back-board 3.

The bent arm 5, above its point of fastening to bar 6, is curved outwardly to clear the bar 8, and at its upper end carries a pawl 9 which engages with a ratchet wheel 10. Near the lower bent over end of arm 5 there is an opening to receive a clamping screw to secure the turned over extremity of the pendulum rod 11 on which is received the bob 12, movable up and down on said rod and adjustable thereon by means of the nut 13.

When the electro-magnet 1 is energized, it moves its armature 4, to the right, from the position shown in Fig. 3, to that shown in Fig. 4, thus causing the pawl 9 to engage with a tooth of ratchet wheel 10 and turn said wheel. When the electro-magnet 1 is

deenergized, the backward swing of the pendulum causes pawl 9 to run over the 50 ratchet teeth.

The intermittent energizing of the magnet is accomplished by the following means: Supported on the bar 6 is a wire frame 14, in which is placed a curved glass tube 15, containing mercury. A circuit terminal 16 enters said tube at one end for a considerable distance. A circuit terminal 17 enters said tube near the other end. Said terminals are connected to the battery 18, or other source of current, and the circuit includes the coil of electro-magnet 1. When the pendulum hangs vertically, as in Figs. 1 and 2, the mercury is out of contact with terminal 17, and the magnet is not energized. When the bob is swung to the left, as shown in Fig. 3, circuit is established at terminals 17, and when said bob is swung to the right by the attraction of magnet 1 upon its armature 4, as in Fig. 70 4, circuit is broken at said terminal 17.

Any suitable clock-train may be interposed between ratchet wheel 10 and the shaft which actuates the clock-hands on the dial 19.

I claim:

1. An electric time mechanism, comprising a pendulum, a time train actuated thereby, an electromagnet, an armature for said magnet supported on said pendulum, 80 a ring support on said pendulum, a removable bent tube containing mercury and having diverging arms separated for a distance greater than the maximum diameter of said ring and seated in said ring, and terminals entering said tube and in circuit with said magnet.

2. The combination with a clock train having a ratchet wheel, an insulated support, a flexible member secured to the support, a yoke carried by the flexible member, a pendulum carried by the flexible member, a U-shaped tube containing mercury seated in said yoke and provided with terminals extending into the ends of the 95 tube, one of said terminals being in con-

stant communication with the mercury, a magnet adapted to move the pendulum, a circuit having connection with the terminals and with the magnet, and an upstanding curved spring arm secured to the flexible member and having a pawl pivoted thereto to engage the ratchet wheel and having a bearing at one end against the spring

arm adapted to hold the pawl against the ratchet wheel.

In testimony whereof I have affixed my signature in presence of two witnesses.

SAMUEL G. RHODES.
